Fig. 1

Fig. 2

Fig. 3

Fig. 4

FIG. 1 is an elevational view of a bottle cap showing my new design, wherein the apex of the cap has a short cylindrical extension; and

FIG. 2 is a plan view of the same.

FIG. 3 is an elevational view of a bottle cap showing a modification of my new design wherein the apex is smoothly rounded; and

FIG. 4 is a plan view of the same.

The characteristic features of my bottle cap design reside in the continuous outward flare from the apex to the base, the solid annular ring at the base, and the tapering

grooves extending from said base toward the apex, and disappearing intermediate the base and apex, all as shown.

I claim:

The ornamental design for a bottle cap, as shown and described.
